Primary Examiner — Philip S Hyder*Assistant Examiner* — Keith Frank(74) *Attorney, Agent, or Firm* — J. Peter Paredes; Rosenbaum IP, P.C.(57) **CLAIM**

The ornamental design for a food package, as shown and described.

DESCRIPTION

FIG. 1 is a perspective view of our new design in the closed configuration;

FIG. 2 is a front elevation view thereof;

FIG. 3 is a rear elevation view thereof;

FIG. 4 is a side elevation view;

FIG. 5 is an opposing side elevation view thereof;

FIG. 6 is a top plan view thereof;

FIG. 7 is a bottom plan view thereof;

FIG. 8 is a perspective view of our new design in the open configuration;

FIG. 9 is a front elevation view thereof;

FIG. 10 is a rear elevation view thereof;

FIG. 11 is a side elevation view thereof;

FIG. 12 is an opposing side view thereof;

FIG. 13 is a top plan view thereof;

FIG. 14 is a bottom plan view thereof; and,

FIG. 15 is a second perspective view thereof, showing unclaimed environmental subject matter, and the broken line showing in FIG. 15 depicts environmental subject matter that forms no part of the claimed design.
